H. B. PLUMB

LOCK

Filed Oct. 19, 1927

H. B. PLUMB, INVENTOR.

B. C. HARRIS & CO., ATTORNEYS.

UNITED STATES PATENT OFFICE.

HENRY B. PLUMB, OF BROOKLYN, NEW YORK, ASSIGNOR TO EAGLE LOCK CO., OF NEW YORK, N. Y., A CORPORATION OF CONNECTICUT.

LOCK.

Application filed October 19, 1927. Serial No. 227,090.

My invention relates to locks, and has special reference to locks that are particularly adapted for use on the doors of safe deposit boxes.

5 One of the objects of my invention is to provide a lock for the doors of safe deposit boxes which is simple in construction and reliable in operation.

Another object of the invention is to provide 10 a lock for safe deposit box doors in which novel and improved safe guarding means is provided.

A further object of the invention is to provide 15 a master-key operable mechanism for locks which is adapted to be rendered inoperative from the outside of the lock-case.

The several features of the invention, whereby the above-mentioned and other objects may be attained, will be clearly understood 20 from the following description and accompanying drawings, in which:

Figure 1 is a front side view of a lock embodying the features of the invention in their preferred form, the lock bolt being 25 shown projected and a portion of the front cover plate of the lock-case being broken away;

Fig. 2 is a sectional view, partly in elevation and on an enlarged scale, taken on the line 2-2 of Fig. 1;

Fig. 3 is a view corresponding to Fig. 1, but showing the lock-bolt in retracted or unlocked position and the front cover plate of the lock-case removed;

35 Fig. 4 is a view corresponding to Fig. 1, but showing the master-key operable mechanism after it has been rendered inoperative;

Fig. 5 is a rear side view of the lock with the parts shown in the same position as in 40 Fig. 1;

Fig. 6 is a similar view partly broken away but with parts of the lock in the position shown in Fig. 4;

Fig. 7 is a detail view in perspective of 45 a plug or closure member forming a component part of the lock; and

Figs. 8, 9 and 10 are detail side views of tumblers that constitute component parts of the lock.

50 The lock illustrated in the drawings is provided with a case 2 and a lock-bolt 4 having two posts or fences 6 and 8. Associated with the fence 6 are tumblers 10 having gatings 12, and associated with the fence 8 are

tumblers 14 having gatings 16, the latter 55 tumblers being in the form of levers that are pivoted on a pin 17 and are pressed downwardly by springs 19. To retract the lock-bolt the tumblers 10 are first lifted to position their gatings in alinement with the 60 fence 6 by means of a key inserted in a key plug 18, and then the tumblers 14 are lifted to position their gatings in alinement with the fence 8 by means of a key inserted in a key plug 20, the key plug being suitably connected with the lock-bolt so that upon the continued movement thereof after the tumblers 14 have been thus positioned, the lock-bolt may be retracted. In the use of 65 the device on the doors of safe deposit boxes, 70 the tumblers 10 are adapted to be operated by means of a guard or custodian's key, and the tumblers 14 by means of a change or renter's key.

Except as hereinafter described, the parts 75 above referred to may be of a well known construction.

In the use of the lock illustrated in the drawings, the keys are preferably shipped to the safe deposit box company separate 80 from the locks, and in accordance with my invention novel and improved means is pro-

vided whereby the proper change or renter's key for the lock of any particular box can only be determined after the box has been 85 rented. It is desirable, however, that the custodian shall be able to lock and unlock the door of the box in order to display the boxes to prospective renters. To provide for this, my improved lock is provided with 90 mechanism whereby the custodian may operate any of the locks by means of a single master-key, but provision is made whereby this mechanism may be rendered inoperative 95 after the box has been rented. This master-

key mechanism comprises a master-key tumbler 22 which is provided with a laterally extending pin 24 that extends through slots 26 in the several tumbler levers 14. The slots 26 are suitably arranged in the several 100 tumblers so that upon turning the master-key plug 20 to raise the master-key tumbler 22, the pin 24 by engagement with the upper portions of the walls of the slots 26 will raise the several tumblers 14 so as to position their gatings in alinement with the fence 8, and thus permit the lock-bolt to be retracted by means of the master-key. 105

It may be noted that this master-key mechanism, including the tumbler 22 and the pin 24, as thus described, is of a common construction.

5 In the illustrated construction in order to render the master-key mechanism inoperative, the pin 24 is detachably secured to the tumbler 22 and may be removed from the outside of the lock-case. To provide for 10 this the pin 24 is in the form of a screw having a slotted head 25 arranged on the outside of the lock-case and having its inner end screw-threaded into an aperture 27 in the tumbler 22, the screw extending through a clearance slot 29 in the lock-bolt. Upon 15 removing the screw 24 it will be apparent that the lock can no longer be operated by means of the master key.

20 In order to determine the proper change or renter's key to use on any particular lock, the lock-bolt carries a designating number on its outer face which is visible through an opening 28 in the rear wall of the lock-case and the proper change or renter's key 25 for the lock carries a corresponding number. Before renting the box, however, this opening is closed so as to conceal the number on the lock-bolt, by a plug 30 which is held in place by the head 25 of the pin or 30 screw 24, the pin or screw extending through a clearance slot in the plug and the head of the screw substantially covering the clearance slot. With this construction, upon removing the screw 24 after the box has been 35 rented to render the master key mechanism inoperative, the plug 30 may be removed so as to uncover the designating character on the lock-bolt, whereupon the proper change key may be determined.

40 As shown in Figs. 1 and 2 of the drawings, when the lock bolt has been projected and before the master key mechanism has been rendered inoperative, the master key tumbler 22 and one or more of the change key tumblers are held in a slightly elevated 45 position by the screw 24, the downward movement of the screw being limited by engagement with the lower end wall of the clearance slot in the plug 30. In the illustrated construction, the slot is not made 50 longer for the reason it is desirable that the head of the screw shall substantially cover the slot in all positions of the screw. It may be noted, however, that the master key tumbler and the change key tumblers drop 55 sufficiently to dog the bolt which, of course, is all that is necessary.

50 In order that the lock manufacturer may easily change the number of the lock-bolt after the renter has given up the box to which the lock has been applied, the number is affixed on a plate 32 which is detachably secured by solder, rivets or other suitable means on the lock-bolt.

65 In order to prevent the screw 24 from be-

ing reinserted, a blocking plate 34 in the form of a tumbler is pivoted on the pivot pin 17 between the master key tumbler 22 and the foremost one of the change key tumblers 14, said blocking tumbler being 70 pressed downwardly by a spring 36. When the screw 24 is in place the blocking tumbler 34 rests thereon, but upon removing said screw the blocking tumbler is permitted to drop down so as to cover the screw-threaded aperture for the screw in the master key tumbler, and thus block said aperture, (Fig. 4). As shown the blocking tumbler 34 when in blocking position and when the bolt has 75 been projected, assists in dogging the bolt and is lifted out of dogging position by means of the change key when the latter is turned to retract the bolt.

80 As will be evident to those skilled in the art, my invention permits various modifications without departing from the spirit thereof or the scope of the appended claims.

85 What I claim is:

1. A lock having, in combination, a lock-case having an opening therein, a closure for said opening, a lock-bolt provided with a fence and having a designating character thereon visible through said opening in the lock-case when said closure is removed, a tumbler having a gating adapted to be moved by a change key to position said gating in alignment with said fence, a tumbler having a gating adapted to be moved by a master key to position its gating in alignment with said fence, a member for securing said closure in place over said designating character and detachably secured to said master key tumbler and suitably arranged to move said change key tumbler to position its gating in alignment with said fence upon operation of said master key tumbler, said member being adapted to be removed to render said change key tumbler inoperative by means of the master key and to permit removal of said closure from over said 100 designating character.

2. A lock having, in combination, a lock-case having an opening therein, a closure for said opening, a lock-bolt provided with a fence and having a designating character thereon visible through said opening when said closure is removed, a tumbler having a gating adapted to be moved by a key to position said gating in alignment with said fence, a pin for detachably securing said closure in place over said designating character and suitably arranged with relation to said tumbler to permit it to be moved to move said tumbler to position its gating in alignment with said fence, and means for thus moving said pin comprising a member to which the pin is detachably secured.

3. A lock having, in combination, a lock-case having an opening therein, a closure for said opening, a lock bolt provided with

a fence and having a designating character thereon visible through said opening when said closure is removed, a tumbler having a gating adapted to be moved by a change 5 key to position said gating in alinement with said fence and having a slot therein, a tumbler having a gating adapted to be moved by a master key to position its gating in alinement with said fence and having an 10 aperture therein, a member extending through said slot in said change key tumbler and detachably secured in the aperture in said master key tumbler and suitably arranged to move said change key tumbler to 15 position its gating in alinement with said fence upon operation of said master key tumbler, said member when in place serving to secure said closure over said designating character and when removed permitting removal of said closure and rendering said 20 change key tumbler inoperable by means of the master key.

4. A lock having, in combination, a lock-case having an opening therein, a closure 25 for said opening, a lock-bolt having a designating character thereon visible through said opening when said closure is removed, mechanism for dogging the lock-bolt and for permitting the lock-bolt to be projected and 30 retracted by means of a change key, and comprising mechanism whereby the lock-bolt may be projected and retracted by means of a master key, said master key mechanism comprising a member removable from the 35 outside of the lock-case and serving when in position in the lock to hold said closure over said designating character and when removed to permit said closure to be removed and to render said mechanism inoperable by 40 means of the master key.

5. A lock having, in combination, a lock-bolt having a fence, a tumbler having a gating and a slot therein adapted to be moved by a change key to position said gating in alinement with said fence, a tumbler having a gating adapted to be moved by a master key to position its gating in alinement with said fence, and a member extending through said slot in said change key tumbler and secured to said master key tumbler whereby upon operation of the latter tumbler said member may move said change key tumbler to position its gating in alinement with said fence, said member being removable so as to prevent said change key tumbler from being again operated by means of the master key.

6. A lock having, in combination, a lock-bolt having a fence, a tumbler having a gating and a slot therein adapted to be moved

by a change key to position said gating in alinement with said fence, a tumbler having a gating adapted to be moved by a master key to position its gating in alinement with said fence, said master key tumbler having 65 a screw-threaded aperture therein, a member extending through said slot in said change key tumblers and screw-threaded into said aperture in the master key tumbler so as to be removably secured thereto whereby upon 70 operating the master key tumbler said member may move said change key tumbler to position its gating in alinement with said fence, and a blocking plate held in unblocking position when said member is secured to 75 said master key tumbler but being moved into position so as to block said aperture in said master key tumbler when said member has been removed, so as to prevent said member from being reinserted in its said aperture 80 in the master key tumbler.

7. A master key mechanism for a lock of the type provided with a lock-bolt having a fence and tumblers having gatings adapted to be moved by a change key to position the 85 gatings in alinement with the fence to permit the lock-bolt to be retracted having, in combination, a tumbler adapted to be moved by a master key to position its gating in alinement with said fence, and a member secured to the master key tumbler for moving said change key tumblers to position their gatings in alinement with said fence upon operating said master key tumbler, said member being adapted to be removed from 90 the master key tumbler so as to prevent said change key tumblers from being operated again by means of the master key.

8. A master key mechanism for a lock of the type provided with a lock-bolt having a fence, and tumblers having gatings adapted to be moved by a change key to position the gatings in alinement with the fence to permit the lock-bolt to be retracted having, in combination, a tumbler adapted to be 100 moved by a master key to position its gating in alinement with said fence, and a member secured to the master key tumbler for moving said change key tumblers to position their gatings in alinement with said fence 105 upon operating said master key tumbler, said member being accessible from the outside of the lock-case to permit it to be removed from the master key tumbler so as to prevent said change key tumblers from being again operated by means of the master key.

In testimony whereof, I have signed my name to this specification this 17th day of October, 1927.

HENRY B. PLUMB.
